UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

INDEX.

Application filed September 27, 1920. Serial No. 413,085.

To all whom it may concern:

Be it known that I, JOHN T. QUIGLEY, a citizen of the United States, and a resident of Boston, in the county of Suffolk and 5 State of Massachusetts, have invented an Improvement in Indexes, of which the following description, in connection with the accompanying drawings, is a specification, like characters on the drawings representing 10 like parts.

This invention relates to paper files and is more particularly concerned with indexes. The invention will be best understood by reference to the following description when 15 taken in connection with the accompanying drawings of one illustrative embodiment thereof, while its scope will be more particularly pointed out in the appended claims.

In the drawings:

20 Figure 1 is a front elevation of a self-indexing file exemplifying my invention;

Fig. 2 is a sectional view on an enlarged scale on line 2—2 of Fig. 1;

25 Fig. 3 is a sectional view also on an enlarged scale on line 3—3 of Fig. 1;

Fig. 4 is a front elevation of a sheet prepared for the making of the filing elements by severing the sheet along certain predetermined lines and then folding the resulting pieces along other predetermined lines; and

30 Fig. 5 is an end elevation of one of the filing elements on an enlarged scale as it appears before being placed in the holder.

35 Referring to the drawings and to the embodiment of my invention which is selected for exemplification, I have shown a file comprising a series of filing elements in the form of record slips 10 abutting edge to

40 edge and held in a suitable holder, herein a frame comprising a pair of channel members 12 provided with inwardly facing flanges 14 presenting channels 16 in which the terminal portions of the filing elements

45 are received. The ends of the channel members are appropriately secured to suitable tie pieces 18. In the present example I have shown a double faced panel, that is to say, one presenting two sets of oppositely

50 facing filing elements and in order to prevent interference of one set with the other I have provided an intermediate wall 20 (see Fig. 3).

55 Referring now to the filing elements, each is formed of a sheet of paper folded to pre-

sent an accordion-like, bendable, compressible and resiliently expansible bar, whose construction is such that it may be bent to allow it to be sprung into or out of the holder, compressed in its cross-section for introduction into the channels and having inherent expansibility whereby it is frictionally held against accidental displacement in the holder. This is most conveniently accomplished by folding the sheet to present a plurality of acute-angled, resiliently expansible bends, herein two folds 22 and two folds 24. In other words, the sheet is folded to present a record tablet 26, a pair of oppositely and inwardly inclined arms 28 and a pair of oppositely and outwardly inclined arms 30 (see Fig. 5).

The described folds have a tendency to open, that is to say, the angles included between the sides of the folds tend to become less acute, the result being that the cross-section of the bar is resiliently expansible in a direction perpendicular to the face of the writing tablet 26 and by simply making the channels 16 a proper depth from front to back the index elements are frictionally held against accidental displacement. Moreover since the cross-section is symmetrical there is a substantial equalization of pressure at both longitudinal edges of the bar and when the edges of the two folds 24 are brought together, as they appear in Figure 2, the arms have a sort of bracing effect. Another important feature of my invention is that owing to the compressible nature of the bars the face of any bar may be pressed inward by the application of the finger thereagainst thus reducing its depth from front to back to a sufficient extent to enable the next adjacent bar to be drawn forward by the finger nail and bent to withdraw its ends from the channels.

The preferred method of making the filing elements is to provide a sheet 32 (see Fig. 4) whose width is the same as the length 100 of each finished filing element, the length of the sheet being such as to permit one or more and preferably several filing elements to be formed therefrom. As an aid in severing the sheet and folding each of its parts 105 to form the filing elements I provide the sheet with a plurality of groups of scored lines, each group comprising a pair of generally parallel lines A—A bounding what is to be the writing tablet, a pair of parallel 110

lines B—B to form the folds 24 and a pair of lines C—C which are to form the free ends of the arms 30 (see Fig. 5). In the present example there is left at one end of the sheet 5 a narrow strip 34 which it is intended to tear off and discard. Also in the present example the scored line C—C of one group is identical with such line of the next succeeding group, that is to say, it is common to 10 the adjacent groups. The best results are secured by making the scorings discontinuous like a series of dashes (see Fig. 4). This is preferred because there is left between the dashes an unscored portion where the fibers 15 of the paper are unweakened and therefore furnish the necessary strength and resiliency for the hinge which they constitute at the bend in the finished filing element.

The first step is to write the names and 20 address or other data on the writing tablets, then sever along the several lines C—C and finally fold the resulting pieces along their support lines as represented in Fig. 5.

Having thus described one embodiment of 25 my invention without limiting myself thereto what I claim and desire by Letters Patent to secure is:

1. In a file, the combination of a series of record slips abutting edge to edge, each slip 30 being formed of a sheet of paper folded to present an accordion-like, bendable, compressible, resiliently expansible bar, and a holder in which said bars are received and frictionally held against accidental displacement by reason of the resiliency expansible 35 characteristic of said bars.

2. In a file, the combination of a series of record slips abutting edge to edge, each slip being formed of a sheet of paper folded to 40 present a plurality of acute-angled, resiliently expansible bends, and a holder in which said slips are received and frictionally held against accidental displacement by reason of the resiliently expansible characteristic of said slips.

3. In a file, the combination of a series of elongated, record slips abutting edge to edge, each slip being formed of a sheet of paper longitudinally folded to present a resiliently 50 expansible bar comprising a record-tablet and a pair of arms transversely inclined with reference to the face of said tablet, and a holder in which said slips are received.

4. In a file, the combination of a series of elongated, record slips abutting edge to edge, each slip being formed of a sheet of paper longitudinally folded to present a resiliently 55 expansible bar comprising a record-tablet and a pair of arms transversely oppositely inclined with reference to the face of said tablet, and a holder in which said slips are received.

5. In a file, the combination of a series of elongated, record slips abutting edge to edge,

each slip being formed of a sheet of paper 65 longitudinally folded to present a resiliently expansible bar comprising a record-tablet and a pair of arms transversely inclined towards each other and with reference to the face of said tablet, and a holder in which 70 said slips are received.

6. In a file, the combination of a series of elongated, record slips abutting edge to edge, each slip being formed of a sheet of paper 75 longitudinally folded to present a record-tablet and a pair of arms transversely inclined from each other and with reference to the face of said tablet, and a holder in which 80 said slips are received.

7. In a file, the combination of a series of 85 elongated, record slips abutting edge to edge, each slip being formed of a sheet of paper longitudinally folded to present a record-tablet, a pair of arms transversely inclined towards each other and with reference to 90 the face of said tablet, and another pair of arms inclined from each other and with reference to the face of said tablet.

8. As an article of manufacture, a sheet prepared for the making of a plurality of 95 distinct filing elements, the same being provided with a series of groups of scored lines arranged in succession, each successive group comprising a pair of lines spaced to provide between them a writing area, and two other pairs of lines spaced from each other and from such area, on opposite sides respectively of the latter.

9. As an article of manufacture, a sheet prepared for the making of a plurality of 100 distinct filing elements, the same being provided with a plurality of groups of scored lines arranged in succession, each successive group comprising a pair of lines spaced to provide between them a writing area, and 105 two other pairs of lines spaced from each other and from such area, on opposite sides respectively of the latter, one of said lines being common to two groups.

10. A filing element comprising an elongated sheet of paper longitudinally folded to present a record tablet, and a pair of oppositely, transversely inclined arms resiliently related to said record tablet and rendering the filing element resiliently compressible in thickness.

11. A filing element comprising a sheet of paper folded to present a record tablet, a pair of arms inclined towards each other, and a pair of arms inclined from each other, 110 said pairs of arms being resiliently related to each other and to said record tablet and rendering the filing element resiliently compressible in thickness.

In testimony whereof, I have signed my 115 name to this specification.

JOHN T. QUIGLEY.
